HINGE JOINT FOR FOLDING RULES

Herman M. Gasstrom, Mount Vernon, N. Y.

Application September 10, 1931, Serial No. 562,076

2 Claims. (Cl. 33—105)

This invention relates to a hinge joint for folding rules.

The object of the invention is the production of a hinge joint for folding rules adapted to connect the middle sections of said rules.

The second object of the invention is the production of a hinge joint, having members which can be easily clinched to the sections of a folding rule without the use of rivets, pins and the like.

The third object of the invention is the production of hinge joints having members that can be easily formed from sheet metal and the like, and which can be easily united to each other.

The fourth object of the invention is the production of a hinge joint in which one of its members functions as a spacer for the hinge.

In the drawing, Fig. 1 represents a top view in full lines of an exemplification of the improved hinge joint, connected to the middle sections of a folding rule, with the sections of the rule in their extended or open position, and in dotted lines with one of the sections of the rule in its folded position; Fig. 2 shows a top edge view of Fig. 1; Fig. 3 indicates a top view of a fragmentary portion of one of the middle sections of the rule; Fig. 4 is a right hand side view of Fig. 3; Fig. 5 represents a top view of a fragmentary portion of the accompanying middle sections of the rule; Fig. 6 shows a left hand side view of Fig. 5; Fig. 7 shows an enlarged partial section of Fig. 2 on the line 7, 7; Fig. 8 indicates a section of Fig. 7 on the line 8, 8; Fig. 9 is a section of Fig. 7 on the line 9, 9; Fig. 10 represents an enlarged bottom plan view of the members of the hinge joint; Fig. 11 represents an enlarged side view of the female member of the hinge joint; Fig. 12 shows a left hand side view of Fig. 11; Fig. 13 indicates an enlarged side view of the male member of the hinge joint and Fig. 14 shows a left hand side view of Fig. 13.

The hinge joint comprises a male member designated in its entirety by the numeral 20, and a female member designated in its entirety by the numeral 70.

The male member 20 of the hinge joint comprises the top wall 22 and the pair of parallel similar side walls 23 spaced from each other. Each of the latter walls has formed at the lower portion thereof an arcuate shaped flange 24, which extends inwardly at right angles to its wall. A prong 25 extends from each of the flanges 24. With one of the walls 23 is formed the cup shaped spacer extension having the outer cylindrical wall 27 with the opening 28, and the

disc shaped side wall 29. The outer face of the wall 29 is spaced inwardly from the outer face of its accompanying wall 23. The said wall 29 has formed therein a circular recessed portion 32, extending inwardly from the outer face of the wall 29. An axial opening 33 is formed in the recessed portion 32. With the other wall 23 of the male member 20 is formed a cup shaped spacer extension, having the outer cylindrical wall 37 with the opening 38, and the disc shaped side wall 39. The outer face of the wall 39 is spaced inwardly from the outer face of its accompanying wall 23. The said wall 39 has formed therein a circular recessed portion 42, extending inwardly. An axial opening 43 is formed in the recessed portion 42. The cup shaped extension having the cylindrical wall 37 is positioned within the cup shaped extension having the cylindrical wall 27.

One of the middle sections of the folding rule is indicated at 50, and has formed therewith at its lower inner corner the clearance space having the arcuate shaped wall 51. The side faces of the middle section 50 adjacent to its inner end have formed therewith plane recesses 52 and arcuate shaped recesses 53, perpendicular to the recesses 52 formed in the section 50.

The accompanying middle section of the folding rule is indicated at 60 and has formed therewith at its lower inner corner the clearance space having the arcuate shaped wall 61. The side faces of the middle section 60 adjacent to its inner end have formed therewith plane recesses 62 and arcuate shaped recesses 63 perpendicular to the recesses 62 formed with the section 60.

The walls 23 of the male member 20 are seated in the recesses 52, and the flanges 24 are seated in the recesses 53 while the prongs 25 are forced into the sides of the section 50, to clinch the male member 20 of the hinge to the section 50 of the folding rule.

The female member 70 of the hinge comprises the top wall 72 and the pair of similar side walls 73. Each of the latter has formed at the lower portion thereof an arcuate shaped flange 74, which extends inwardly at right angles to its wall. A prong 75 extends from each of the flanges 74. With each of the side walls 73 is formed a disc shaped extension 77. The outer face of each extension 77, is spaced outwardly from its accompanying side wall 73 and has formed therein a disc shaped recessed portion 78 that extends inwardly. In each recessed portion 78 is formed an opening 79.

The side walls 73 of the female member are

seated in the recesses 62 of the section 60, and the flanges 74 are seated in the recesses 63, while the prongs 75 are forced into the sides of the section 60 to clinch the female member to said section.

The recessed portions 78 are seated in the recessed portions 32 and 42 of the male member of the hinge.

A thimble shaped pintle is shown having the 10 barrel 90 and the end flanges 91. The barrel 90 extends through the openings 33 and 43 of the male member of the hinge joint, and the flanges 91 are seated in the recessed portions 78 of the extensions 77 of the female member of 15 the hinge joint, and thereby the male and female members of the hinge joint are adjustably connected to each other.

Various modifications may be made in the invention and the present exemplification is to 20 be taken as illustrative and not limitative thereof.

Having described my invention what I desire to secure by Letters Patent and claim is:

1. In a hinge joint the combination of a male member, comprising a pair of similar side walls 25 spaced from each other, an arcuate shaped flange at the lower portion of each of said walls, a prong extending from each flange, a top wall connecting said side walls, a cup shaped spacer extension integral with the lower portion of each 30 of said walls, said cup shaped extensions being disposed one within the other, a female member of the hinge joint comprising a top wall, a pair of similar parallel side walls spaced from each

other extending from the latter top wall, an arcuate shaped flange at the lower portion of each of the latter side walls, a prong extending from each of the latter flanges, a disc shaped extension integral with each of the side walls of said female member, said disc shaped extensions straddling and bearing against the outer faces of the cup shaped spacer extensions of the male member, and a pintle uniting the disc shaped extensions of the female member and the cup shaped spacer extensions of the male member, the arcuate flanges of the members adapted to be seated in recesses of the sections of a folding rule, and the prongs adapted to be pressed into said sections.

2. In a hinge joint the combination of a male member, comprising a pair of similar side walls spaced from each other, a cup shaped spacer extension integral with the lower portion of each of said walls, said cup shaped extensions being 95 disposed one within the other, a female member of the hinge joint comprising a pair of similar side walls spaced from each other, a disc shaped extension integral with each of the side walls of said female member, said disc shaped extensions straddling and bearing against the outer faces 100 of the cup shaped spacer extensions of the male member, a pintle uniting the disc shaped extensions of the female member and means to fasten the walls of both said male and female 105 members to a pair of the sections of a folding rule.
